BASKET

John H. Holtvoigt, Tipp City, Ohio, assignor to
The Dolly Toy Company, Tipp City, Ohio, a
corporation of Ohio

Application June 20, 1941, Serial No. 392,986

7 Claims. (Cl. 217—122)

This invention pertains to containers, and more particularly to the structure and mode of manufacture of baskets of inexpensive type, including small toy baskets known to the trade as "Easter" baskets.

Heretofore, toy baskets, especially those for the Easter trade, have been imported from Japan at notoriously low prices. The present invention is an endeavor to provide a basket which can compete with the Japanese products, and which, therefore, can be economically manufactured, which will be strong and sturdy, and of pleasing appearance.

A further object of the invention is to provide a basket construction which may be rapidly and easily assembled by unskilled operators.

A further object of the invention is to provide integral bottom and side slats for such basket.

A further object of the invention is to provide a reinforcing and stiffening member and means for interlocking it with the basket structure.

A further object of the invention is to provide an inexpensive means and method of pivotally connecting a handle with the basket.

A further object of the invention is to provide a method of weaving the basket sides with a series of loop members for such purpose.

A further object of the invention is to provide a basket having the advantageous structural features and inherent meritorious characteristics and method of assembly herein mentioned.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawing.

In the accompanying drawing, wherein is shown the preferred, but obviously not necessarily the only form of embodiment of the invention,

Fig. 1 is a perspective view of an assembled basket, partly broken away, embodying the present invention.

Fig. 2 is a perspective view of portions of the disassembled parts.

Fig. 3 is a detail sectional view illustrating the manner of assembly of the parts shown in Fig. 2.

Fig. 4 is a perspective view of one of the bands to be interwoven in the basket sides.

Fig. 5 is a perspective view of a modification of the reinforcing and stiffening ring.

In constructing the present basket, there is employed a blank, preferably of cardboard or other fibrous sheet material, comprising the bottom section 1, and a plurality of integral 5 radially extending relatively spaced arms 2. The blank is scored at 3 at the juncture of the arms 2 with the bottom 1 to enable the arms 2 to be bent upright into substantially perpendicular relation with the bottom 1. The ends of the arms 2 are reduced and formed with terminal tenons 4. Interlaced or woven about the upstanding arms or slats 2 are flexible strips 5, which are ordinarily of paper or the like, and which are variously colored. The interwoven strips may be continuous and interlaced round and round the basket.

However, as an economical and rapid method of effecting such assembly, the interwoven strips 5 preferably, but not necessarily, comprise endless bands, as shown in Fig. 4. Such bands are produced by first forming a tube of the sheet material and then cutting the tube transversely into short sections or bands 5. Such bands are disposed in superposed alternating relation over and under the succeeding arms or slats 2. Adjacent the top of the basket walls a flat ring 6 of cardboard having therein spaced slots or mortises 7 is positioned over the tenons 4. This ring is relatively stiff and greatly 20 reinforces and strengthens the basket structure. The reinforcement ring 6 is locked in place by a band or strip 8 interlaced over and under succeeding tenons 4 of the slats 2 and secured thereto at spaced intervals by stapling as at 9. 25 The final strip or band 8 may be of cardboard or of wood veneer, or other thin flexible material which will afford a finished appearance to the basket. Likewise, the bottom 1 and slats 2 may be formed from wood veneer or other fibrous material in lieu of being cut from cardboard.

A handle bow 10 may be fixedly attached to the body of the basket, but is preferably pivotally connected thereto. It may be attached 30 to opposite slats 2 of the basket body by eyelets or other pivotal couplings. However, as an inexpensive mode of assembly capable of being quickly effected, the opposite body slats 2 are formed with holes 11 therein, which are punched 35 simultaneously with the initial cutting of the blank. The ends of the handle bow 10 are stapled through such holes to a bit of cardboard or washer 12 inside the basket, by an ordinary stationery staple 13 thrust through the end of the handle and idly through the enlarged holes

11 and thence through the washer 12 and clenched. This enables the handle to be oscillated from upright to a retracted position in either direction. In such movement the staple 13 merely rotates to and fro within the hole 11 in the basket slat. Such stationery staples are less expensive than eyelets and are more easily inserted by an ordinary stapling device.

In lieu of the flat reinforcement ring 6, such member may be formed into channel shape, as shown at 6' in Fig. 5, with the slots or mortises to receive the tenons 4 in the crown of the channel. Due to the fact that when in annular form the inner wall of such inverted channel is of less length than the outer wall thereof, it is desirable to form such channel ring from softened or moist material under pressure.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A basket, comprising a body portion and a handle therefor including a bottom section and integral spaced upstanding slats formed from a single piece of fibrous material, a filling of strip material interwoven in alternating direction between and about the slats, tenons comprising reduced ends of the slats, stop shoulders on the slats afforded by the reduced ends thereof, a reinforcement ring of fibrous material disposed in a plane substantially perpendicular to the slats having spaced slots therein through which the reduced ends of the slats extend, both above and below which reinforcement ring the filling of interwoven strip material is disposed, certain opposite slats having holes therein, a flat bail handle strip, the ends of which exteriorly overlap the holes in the slates, washers interiorly overlapping the holes in the slats, wire staples interconnecting the ends of the handle strip and the washers through the holes in the slats independently of the slats, and peripheral notches in the reinforcement ring within which the bail handle is engageable for releasably maintaining the bail in upright adjusted position, the construction and arrangement being such that the staples freely rotate in the holes upon disengagement from the notches of the bail handle for swinging movement thereof.

2. A basket, including a bottom section and integral upstanding spaced slats formed from sheet material, tenons formed on the ends of the slats, integral stop shoulders formed on the slats, a plurality of endless bands of strip material interwoven in alternating relation about the upstanding slats, a peripherally notched reinforcement ring having therein a succession of mortises in which the tenons of the slats are

engaged seated on the stop shoulders, and a swinging bail of flat strip material pivotally connected with the basket and engageable in the peripheral notches of the reinforcement ring for adjustably supporting said bail in upright position.

3. In a basket construction, a receptacle including integral bottom and side walls, a flat swinging handle bail therefor, the side walls of the receptacle having enlarged holes therein which are overlapped by the ends of the flat swinging handle bail, wire staples having relatively spaced legs extending through the ends of the bail and thence freely through the enlarged holes in the sides of the basket without engagement therewith, and stop members overlying the holes of the side walls opposite the ends of the bail through which the staples are extended and with which they are secured, the construction and arrangement being such that the bail is mounted on the receptacle for free pivotal motion wherein the wire staples rotate to and fro within the enlarged holes in the receptacle wall.

4. A basket including a bottom, upstanding spaced slats formed integrally therewith, a series of flat endless bands interlaced one above another about succeeding slats, tenons formed on the ends of the slats, a flat ring disposed in transverse plane substantially perpendicular to the slats and having spaced mortises therein through which the slat tenons extend, and an endless flat band interlaced about the slat tenons above the flat ring.

5. As an article of manufacture, a paper and cardboard basket, including a bottom and integral relatively spaced slats cut from a cardboard sheet, the slats being upturned into substantially perpendicular relation with the bottom

portion, a series of endless paper bands interwoven in alternating relation between and about the spaced slats, terminal tenons formed on the slats, stop shoulders formed on the slats adjacent to the terminal tenons, an endless reinforcement ring of cardboard having therein a succession of slots through which the tenons of the slats project disposed in a plane substantially perpendicular to the slats and resting on the stop shoulders in superposed relation with the interwoven endless paper bands, and an additional endless ring interwoven between and about the ends of the tenons projecting above the reinforcement ring, opposite slats of the assembly having enlarged holes therein, a handle bail, the ends of which exteriorly overlap the enlarged holes in the opposite slats, separate pieces of material interiorly overlapping the enlarged holes, and wire staples transfixing the handle bail and the pieces overlapping the holes at the inner sides thereof independently of the slat containing the hole.

6. As an article of manufacture, a basket structure including a bottom, substantially upright relatively spaced slats connected to the margin of the bottom, a plurality of separate independent endless filler bands interwoven reversely between and about the slats, a flat reinforcement member having therein a succession of slots through which the ends of the slats project disposed in a plane perpendicular to the slats, and an endless band interwoven between and about the ends of the slats projecting beyond the reinforcement member.

7. A container having a bottom and side walls, the latter being provided with oppositely disposed enlarged openings, a handle bail the ends of

which extend in exterior overlapping relation with the holes in the side walls of the container, pieces of material of larger area than the holes overlapping the holes at the inner sides of the side walls, wire staples transfixing the portions of the bail handle which overlap the holes and the pieces of material which overlap the holes at the inner sides of the holes, and connect said

portions through the holes independently of the holes containing side walls, the construction and arrangement being such that the wire staples freely turn within the holes and interconnect the said interior hole overlapping pieces positively with the handle bail for unison oscillatory motion.

JOHN H. HOLTVOIGT.
